MEANS FOR THERMALLY GENERATING
ELECTRICITY

Edgar Underwood, Gary, Ind.

Application December 22, 1932, Serial No. 648,513

2 Claims. (Cl. 136—4)

My invention relates to improvements in means of thermally generating electricity, and it consists in the combinations, constructions, and arrangements herein described and claimed.

5 An object of my invention is to provide an efficient method and means of thermally generating electricity.

Another object is to provide means whereby heat energy may be rapidly transferred from the cold junctions of a thermopile to its hot junctions.

10 A further object is to provide a fan or air pump means whereby cool air may be rapidly passed over the cold junctions and the temperature of a portion of this air then raised by compression and 15 the remainder of the air re-heated by conduction for passing into the combustion chamber in which the hot junctions of my thermopile are heated.

A further object of my invention is the efficient employment of extremely short thermo-couple elements to the end that the electrical resistance of the thermo-couple elements may be substantially decreased.

20 A further object is to provide means whereby the thermo-couple elements may be supported even when embedded in a comparatively thin and flexible insulating roof or wall.

A further object is to provide means whereby the hot junctions of the thermo-couple may be protected from direct contact with the heated 25 particles of combustion in the furnace chamber.

A further object is the provision of a thin flexible insulating wall permitting the safe employment of short thermo-couple elements.

30 A further object of my invention is to provide means whereby the voltage of a thermoelectric generator may be regulated by controlling the fuel input.

A further object is the provision of means whereby the thermo-couple elements and the insulating wall may be securely supported.

35 A further object is the provision of means whereby the heat which is transferred by conduction from the hot junctions to the cold junctions of a thermopile may be rapidly removed from the cold junctions.

40 A further object is the pre-heating of the fuel by heat energy derived from the heated products of combustion after the products of combustion have passed from the combustion chamber of the furnace.

45 Other objects and advantages will appear in the following specification, and the novel features of the invention will be particularly pointed out in the appended claims.

50 55 My invention is illustrated in the accompany-

ing drawings, forming part of this application, in which

Figure 1 is a partly broken away top plan view of a preferred form of a thermoelectric generating system embodying my invention.

5 Figure 2 is a section taken along the line 2—2 of Figure 1, certain portions being shown in section 1.

Figure 3 is a section taken along the line 3—3 of Figure 2.

10 Figure 4 is a section taken substantially along the line 4—4 of Figure 1.

Figure 5 is a section taken along the line 5—5 of Figure 4.

15 Figure 6 is a section taken along the line 6—6 of Figure 4.

Figure 7 is a front elevational view of the construction shown in Figure 1.

20 Figure 8 is a partly sectional partly diagrammatic view of a fuel control means whereby the voltage of my thermoelectric system may be regulated.

Figure 9 is a fragmentary vertical sectional view of a modified form of my invention.

25 Figure 10 is a broken vertical section through the lower end of one of the thermocouples, and

Figure 11 is a sectional view taken on line 11—11 of Figure 10.

In carrying out my invention I make use of a firebox 1 which is preferably mounted above a 30 fireproof floor 2 on a rigid supporting member or base plate 3, having a central opening 4 and being supported on any suitable legs 5. The walls 6 and the bottom 7 of the firebox are preferably made of heat resisting material such as, for instance, 35 asbestos composition bricks.

Above the opening 4 of the plate 3, a rigid frame 8 is provided for supporting a burner means 9 and a primer means 10. The frame 8 may, if desired, be bolted to the bottom of the base 7 of 40 the firebox. The function of the primer 10 is to initially heat and vaporize the fuel in the burner 9.

The top of the firebox comprises a heat insulating and heat resisting board 11, which is preferably of asbestos composition, and is arranged or adapted to provide a seal whereby the products of combustion are prevented from passing from the roof of the firebox.

45 A plurality of hereinafter to be described thermo-couple elements are imbedded in and extend through this insulating board. The upper portion of the rear wall of the firebox is provided with a preferably rectangular conduit 12 through which the heated products of combustion pass out of 55

the firebox, through an air conduit 13 to the exterior of my generating system.

The conduit 13 extends from an opening 14 (where air is received from the upper portion of 5 my system) down to the opening 4 in the base plate 3, which supports the firebox.

The lower portion of the conduit 13 is secured to the plate 3 in such a manner that no air may enter the firebox through the opening 4 except the 10 air which is passed downwardly through the conduit 13.

The burner 9 and the primer 10 are supplied with liquid fuel from a tank 15, see Figure 8, by 15 way of a main pipe 16, see Figure 4, to which the burner fuel pipe 17 and the primer fuel pipe 18 are operatively connected. Each of the pipes 17 and 18 pass through the wall of a conduit 13 in an air tight manner. The primer pipe is directly connected to the primer substantially as shown. The fuel pipe passes to the rear and then upwardly through the conduit 13 and then passes into the exhaust conduit 12, where it is coiled as is indicated at 19, so that the fuel may be thoroughly vaporized before it passes out of the inner end 25 of the conduit 12, and is operatively connected to the burner 9. Each of these pipes may be provided with any suitable valve means such as for instance hand valves 20 and 21.

Now referring to Figures 1 to 4 inclusive, it will 30 be seen that a plurality of parallel pipes 22 are supported above the firebox by brackets 23, which are mounted on top of the firebox at the front and the rear of my electric generator substantially as shown in Figure 1. These brackets may be of 35 any suitable construction adapted to support the pipes and at the same time permit a substantially unobstructed flow of air from the front to the rear of the generator. Each of these pipes may be insulated in any suitable manner, such as for instance, by an insulating sleeve 24. This insulating sleeve may be made of asbestos or any other suitable construction adapted to withstand a certain amount of heat, and at the same time provide an electrical insulation between its pipe and the strap 40 and thermocouple means now to be described.

Now referring particularly to Figure 2, it will be seen that the pipes 22 support a plurality of thermocouples by means of straps 25. These straps may be made of a steel alloy and for the purpose 50 of illustration are shown as each consisting of two strips which are bolted together at the top of the pipes, as is indicated at 26, and extend downwardly to support the thermocouple elements 27. These strips are secured to the opposite sides of a thermocouple unit by means of a brad or bolt 28 55 which passes entirely through the cold junction 29 of the thermocouple unit and each of the strips, and by welding.

These thermocouple elements are, of course, of 60 metal construction. While these may be made of any metals having an electrical potential difference when heated, in the present instance I have used a nickel chrome alloy strip 30 in combination with a copper nickel alloy strip 31. I have 65 found this combination of alloys to be suitable for the purpose intended, and to have a fairly low resistance when heated.

The copper nickel alloy when heated acts as a 70 positive or negatively charged element, and the nickel-chrome alloy acts as a negative or positively charged element.

It will be observed that these elements are of 75 such a shape that they may be brought together at their hot and their cold junctions of the thermocouple so as to form a V, the cold junction end

and the hot junction end being parallel and offset with respect to each other, and these two ends being connected together by an inclined portion which is approximately one third the length of the entire length of these elements.

The hot junction may be joined together in the same manner as the cold junction with the exception, of course, that the straps are not connected to the hot junction. The hot junction is shielded from direct contact with the heated products of 10 combustion by a metal casing 80 which is preferably cup-shaped and is fixedly secured to the hot junction in any suitable manner such as, for instance, rivets or bolts 28, or by welding. The preferred construction of the casing 80 is illustrated in Figures 10 and 11. The couple elements 30 and 31 preferably are welded together and may be provided also with a rivet, if desired. Welded to opposite sides of the connected ends of the elements 30 and 31 are plates 80a and 80b 20 which extend beyond the vertical sides and bottom edges of the elements to form a channel in which weld material 80c is deposited to form with the said plates of the inclosing cup or casing 80. The welding of the elements 30 and 31 together 25 and the forming of the casing 80 as described, not only protects the couple elements, but reduces the resistance of the couple and thus increases its efficiency. The casing 80 together with the inclosed ends of the couple elements constitute heat absorbers.

By referring to Figures 1 and 4 it will be seen that one of the terminal strips 32 is connected to the rear far portion of the thermopile, while the other of the terminal strips 33 is connected to the 35 near front end of the thermopile.

The portion of the thermopile construction which extends above the insulating board 11 is enclosed in the metal casing or cover 36 which in combination with the board 11 forms an elongated air casing or conduit 37 through which air is blown to cool the cold junctions of the thermopile and the supporting straps depending from the pipes 22. An important function of these straps 40 is that they serve as radiators and conduct the 45 heat rapidly away from the cold junctions and due to their comparatively large surface area transmit this heat rapidly to the air stream passing through the casing.

The front portion of the cover 36 extends beyond 50 and in front of the firebox 1, and supports an electrical fan means 39, having a motor 40.

In the rear and opposite portion of the air casing 37 a funnel shaped air exhaust conduit 41 is provided for the purpose of constricting a major 55 portion of the air after it has passed over and has been heated by part of the thermopile construction which extends above the insulating board 11. This air exhaust is provided with a funnel portion 42, the outer peripheral edge of which is 60 welded or otherwise connected in a substantially air tight manner to the inside of the casing 36, see Figure 5, to the end that the air driven through the casing may be forced into the funnel portion 42. This funnel portion 42 is provided with a plurality 65 of openings 43 through which a minor portion of the air stream, after passing by the thermopile, may pass around the outside of the funnel tube 44, for the purpose which will become apparent as the specification proceeds. The main or 70 major portion of the air stream is forced by the fan 39 into the funnel portion 42 to pass through the tube 44 and out of the rear end of the casing 36.

This funnel tube is provided with a plurality 75

of metal fins 45 which may pass entirely through the funnel and project on either side thereof substantially as shown in Figure 5. The outer ends of these fins preferably do not touch the surrounding walls of the air casing 37, as it is their function to heat the minor portion of the air stream in a manner more fully set forth in the description of the operation of my generating system.

10 The minor stream, after passing between and being heated by these fins, passes out of the casing 37 through the opening 14 in the rear bottom portion 37' of the casing, and thereafter passes downwardly through the conduit 13 and discharges into the hollow interior of the firebox 1.

15 In Figure 8 I have shown an electro-magnetically operated switch and valve construction whereby the voltage generated in my thermoelectric generating system may be maintained with 10 in predetermined limits, and thereby kept substantially constant during the normal operation of my system. This switch and valve construction includes a valve means 46, a solenoid 47, and an electric switch means 48. Each of the 15 means 46, 47 and 48 may be mounted on any suitable support, such as for instance a switchboard 49, and may be operatively connected together, substantially as shown.

The valve means 46 includes a chambered body 10 portion 50 and an exteriorly threaded cup shaped packing ring 51, having a cap 51'. The body portion 50 is provided with a valve chamber 52 having inlet and outlet ports 53 and 53', operatively connected to the fuel supply tank 15 and 15 the main pipe 16, substantially as shown.

15 The valve chamber 52 is provided with a valve seat 55 which is adapted to receive the valve 56 which is rigidly secured to a rod 57. This rod 57 passes through the packing ring cup member 51, and at its upper end is rigidly secured to a reciprocating plunger armature 58; this plunger armature is operated by an electrical energizing coil 47 in such a manner that when the coil is energized the plunger 58 tends to move downwardly, thus closing the valve 56 on the valve seat 55. The plunger armature 58 is connected at its upper end to a vertical rod 59 which in turn is pivotally connected at its upper end to a switch arm 60 which is pivotally mounted at 43' 10 in an opening 44' and is arranged to connect the switch terminals 61 when the rod 59 is pressed upwardly by an encircling expansion spring 62 positioned between an abutment 63 fixedly connected with the rod 59 and the uppermost of the 15 brackets 45' supporting the coil 47.

The terminal 61 and the coil 47 may be electrically connected to the terminal members 32 and 33, substantially as indicated in Figure 8.

From the foregoing description of the various 10 parts of my invention, the operation thereof may be thoroughly understood.

When the generator is cold, it will be noticed that the valve 56 is kept in its open position by the tension of the spring 62 surrounding the rod 15 59. The liquid fuel from the tank 15 may, therefore, pass into the primer feed pipe 18, and may be admitted to the primer by opening the hand valve 21. When the liquid fuel in the primer is ignited it, of course, heats the burner 9. A sufficiently hot fuel may be admitted to the burner 9 10 by opening the hand valve 20. The fuel upon entering the burner 9 is, of course, vaporized and may be ignited.

The hot junctions of the thermopile become 15 heated when the burner is in operation, and the

exhaust products of combustion pass out of the system through the rectangular exhaust conduit 12. In passing through the conduit 12 the heat of these products of combustion almost immediately vaporize the liquid fuel in the coil of the pipe 17. The hand valve 21 may now be closed, shutting off the fuel from the primer 10. The heating of the lower or "hot" junctions of the thermopile generates an electromotive force proportional to the difference in temperature between 10 the hot junctions and the cold junctions of the thermopile. The terminal strips 32 and 33, therefore, if connected as indicated in Figure 8, pass a current through the conductors 65, 66, 67, 68, 69, 70, 71, 72, 73, and 74, and the switch means 15 15, 16, 17 and 48 to the motor 40 and the coil 47 in a manner which may readily be understood by referring to this figure. This current will soon be sufficient to energize the motor, but if desired the motor may be initially started by operatively 20 connecting it to any other suitable source of electrical supply.

The fan 39 drives an air stream around and between that portion of the thermopile constructions above the insulating board 11. This air 25 stream blowing against the cold junctions and the straps supporting them by reason of their connection with the pipes 32, rapidly withdraws the heat from the cold junctions thereby maintaining a substantial difference in temperature 30 between the cold and the hot junctions.

Here the straps 25 have a very important function. They are so connected to the cold junctions and have such a large radiating surface that the heat is quickly transferred from the cold 35 junctions to the air. It will be observed that each of these straps are thermally and electrically insulated from the pipes 22 by the asbestos sleeves 24. After the air stream has passed through a portion of the thermopile construction above the 40 board 11, the major portion of the air stream is forced by the funnel portion 42 of the air exhaust conduit 41 into the comparatively small funnel tube 44. The tube 44, of course, reduces the size of the air stream, and thus compels a 45 larger number of heat units to pass through a square inch taken cross sectionally of the air stream in the tube than would pass through a square inch taken cross sectionally of the air stream in front of the funnel shaped conduit 41. 50 This condition tends to heat that portion of the fins positioned within the tube 44, and this heat is conducted to the outer portion of the fins. A minor portion of the air stream passes through the openings 43 and between the outer portions 55 of the fins 45.

Due to the heating of the fins by the constriction and compression of the air stream as it passes through the conduit 41, the temperature of the minor portion of the air stream is substantially heated before passing downwardly into the conduit 13 and the interior of the firebox. It will thus be seen that a large portion of the heat energy transmitted to the air stream is recovered and utilized in heating the junctions of 65 the thermopile which lie beneath the board 11.

It is, of course, desirable that any electrical generating system should be capable of maintaining a substantially constant voltage at the main terminals of the generator. The valve 56 and 70 switch construction 48 effects a voltage control whereby this object may be attained. The coil 47 and the spring 62 are so designed and adapted that if the voltage is above the maximum voltage at which the system is intended to operate, the 75

voltage is sufficient to cause enough current to flow through the coil to overcome the tension of the spring and set the valve 56 on the valve seat 55. This, of course, shuts off the fuel supply and reduces the temperature of the hot junctions of my thermopile construction. If desired the switch arm 60 may be so arranged as to open the circuit between the switch terminals 61. In this event the fan is, of course, stopped and the fuel supply is entirely cut off and the voltage of the current generated rapidly falls below the predetermined minimum voltage of the system.

Under these conditions the magnetic pull exerted against the tension of the spring 62 is weakened sufficiently to cause the valve to open and the switch lever arm 60 to short the switch terminals 61.

A continuous extreme limit reciprocating movement of the movable elements of the valve and switch construction 45 sufficient to alternately close and open its switch and valve is not, of course, essential to the normal operation of my device. The voltage of the generator may usually be controlled by a small increase or decrease of the magnetic pull on the armature 58 against the tension of the spring 62.

It is readily apparent that a slight increase in the magnetic pull will cause the valve to gradually reduce the amount of the fuel which passes through the valve chamber 52, and into the burner 9. The reducing of the fuel supplied to the burner 9, of course, reduces the potential difference impressed on the generator terminals 32 and 33 and the magnetic pull exerted by the coil 47 and the plunger 58. It is obvious, therefore, that the voltage generated by this system may be controlled within narrow limits, and that these limits may be varied by regulating a rheostat 78 which is placed in series with the windings of the coil 47.

In Figure 9 I have shown fragmentarily a modified form of a thermoelectric generator which is adapted to be water cooled. This generator has a rectangular asbestos composition board 11 supported by a steel plate 81. This plate 81 has integral cup-like portions or corrugations 82 which shield the hot junctions 84 from coming in direct contact with the heated particles of combustion in the combustion chamber 85. These junctions are electrically insulated from the cup-like members 82 by cup-shaped insulators 86. These insulators may, if desired, be made of any suitable material such as, for instance, asbestos or mica compounds or compositions.

The cold junctions 87 of the thermopile may, if desired, be similar in construction to the cold junctions in the preferred form of my invention, and may be similarly secured together. These junctions are, however, soldered or otherwise directly connected to metal bars 88. These bars may be made of copper or copper alloy or any suitable material adapted to serve as good heat conductors.

These bars are provided with openings 89 adapted to receive supporting pipes 22 which may be supported in any suitable manner. The pipes 22 are electrically insulated from the metal bars by means of an insulating sleeve 24. The metal bars 88 are covered by a rectangular metal shield 90 which may be made of a steel alloy. This shield 90 is adapted to cover a plurality of the cold junctions and their bars, and is arranged to be welded or otherwise secured in a water tight manner to a rectangular casing 91, which is provided with a water inlet port 92 and a water outlet port 93.

The shield 90 may be also welded to a rectangular ring 94 having a U-shaped groove 95. This ring may be welded or otherwise connected to the plate 81, and the side walls 96 of the combustion chamber 85 which, of course, contains a burner (not shown), which supplies the heat to this thermopile construction. Any other suitable source of heat may be employed.

The main purpose of the casing 91 is obviously to permit any suitable cooling fluid medium such as, for instance, cold water or liquid sulphur dioxide to be passed around the bars 88 and the cold junctions for the purpose of maintaining a large difference in temperature between the upper and lower junctions of the modified form of my invention.

By the provision of the casings 90 on the hot ends of the couples to reduce resistance and increase heat absorption and by intimately connecting the brackets of hangers 25 as by welding to the upper ends of the couple elements on the opposite side of the insulating partition to provide efficient heat radiation, a high temperature difference can be obtained notwithstanding the use of relatively short thermocouple elements to provide a compact generating apparatus.

By utilizing relatively short couple members, electrical resistance is reduced and by paralleling the absorbers and the hot junctions and likewise the radiators with the cold junctions resistance is further reduced, whereby the general operating efficiency of the generator is greatly improved. The casings or absorbers 90 are able to absorb heat faster than the couple elements can conduct it through the insulating partition to the cold junctions, and thus each absorber in ordinary operation will contain a reserve supply of heat which will result in substantially a uniform electrical output of the generator notwithstanding slight fluctuations in the generation of heat in the combustion chamber. Complemental advantages are effected by the radiators connected to the cold junctions, since the couple elements cannot conduct heat to the cold junctions and the radiators in quantities sufficient to reduce substantially the temperature difference of the hot and cold junctions.

While I have shown certain modifications of my invention for the purpose of illustration, I do not wish to be restricted specifically thereto except as so limited by the appended claims.

I claim:

1. In a thermoelectric generating system of the character described, a combustion chamber, a burner positioned in the combustion chamber, an insulating board forming an upper portion of the boundary of said chamber, a plurality of metal thermocouple strips operatively connected together to form a thermopile extending through the board and having hot junctions projecting into the combustion chamber, and having their cold junctions extending above said board, a plurality of metal supporting and heat radiating means directly connected to said cold junctions for supporting said thermocouple strips in position, means for supporting said supporting and heat radiating means, means for passing an air stream around the cold junctions and the supporting and radiating means, slotted funnel tube means for separating said air stream into a major air stream and a minor air stream and for reducing the cross sectional area of the major air stream, means for passing said minor air stream around said major air stream, and metal heat radiating means secured to said slotted funnel tube.

means, and projecting within and without said funnel tube means for conducting heat from said major air stream to said minor air stream and conveyor means for passing said minor air stream 5 into said combustion chamber.

2. In a device of the character described a combustion chamber provided with insulating walls, an insulating board forming a part of said walls, a burner located in the combustion chamber, a 10 plurality of thermocouple elements passing through said board extending on each side thereof, and being operatively connected together to

form a thermopile having its hot junctions projecting within the combustion chamber and its cold junctions projecting without the combustion chamber, fan and conduit means for driving an air stream around the cold junctions of the 5 thermopile, funnel means for constricting and exhausting a major portion of said air stream and for passing a minor portion of said air stream around the major portion of said air stream, and conduit means for guiding the minor portion of 10 said air stream into the combustion chamber.

EDGAR UNDERWOOD.
